UNITED STATES PATENT OFFICE.

JAMES BEATTIE, OF SHREVEPORT, LOUISIANA.

OIL HEATING-FURNACE.

SPECIFICATION forming part of Letters Patent No. 773,458, dated October 25, 1904.

Application filed April 25, 1904. Serial No. 204,890. (No model.)

To all whom it may concern:

Be it known that I, JAMES BEATTIE, a citizen of the United States, and a resident of Shreveport, Caddo parish, Louisiana, have 5 invented certain new and useful Improvements in Oil Heating-Furnaces, of which the following is a specification containing a full, clear, and exact description, reference being had to the accompanying drawings, forming 10 a part hereof.

My invention relates to oil heating-furnaces; and it consists of the novel features herein shown, described, and claimed.

In the drawings, Figure 1 is a view showing the furnace in elevation and showing the blower and the source of oil-supply, the view being in the nature of a diagram. Fig. 2 is a vertical central section, upon an enlarged scale, on the line 2 2 of Fig. 3. Fig. 3 is a 20 cross-section on the line 3 3 of Fig. 2 and looking in the direction indicated by the arrow. Fig. 4 is an enlarged sectional detail of the oil-nozzle.

Referring to the drawings in detail, my 25 improved oil heating-furnace is built principally of fire-brick and has the usual heating-chamber 5, said chamber being accessible for the insertion and the removal of the metal through the door-openings 6. The heating-chamber is provided with a floor 7, composed 30 of a thick layer of ordinary sand or silica, said sand being embedded in the masonry, so that it will not run away when melted. The heating-chamber 5 discharges into the flue or 35 smoke-stack 8, the bottom of the flue being slightly lower than the floor of the heating-chamber, and a drain-pipe 9 is provided to carry off the slag which results from the heating of the metal. An overhanging bridge- 40 wall 10 is inserted between the heating-chamber and the flue to retard the passage of heat out of the chamber. The ignition-chamber 11 is located immediately below the bridge-wall 12, and the combustion-chamber 13 connects the ignition-chamber with the heating-chamber, said combustion-chamber being in 45 the form of a returned bend extending around the bridge-wall 12. The air-pipes 14 lead from the blower 15 through the wall of the 50 furnace, so that the air discharged through

the pipes from the blower passes through the upper part of the combustion-chamber 13 and strikes the sand floor 7 at an acute angle.

The opening 16 in the front wall provides access to the ignition-chamber 11. The openings 6 and 16 may be covered with doors or not, as desired.

The wall 17, forming the front of the ignition-chamber, is located transversely of the furnace and directly below the right-hand end 60 of the sand floor, there being an opening 18 in the masonry to provide access to this wall, and an air-inlet flue 19 is embedded in the masonry and leads from the opening 18 to the chamber 11. The nozzle 20 is located in the 65 flue 19 in position to discharge through the flue into the chamber 11, and an air-pipe 21 connects the nozzle 20 to the air-pipe 14 or to the blower 15 and an oil-pipe 22 connects the nozzle to the elevated oil-tank 23, the passage 70 through the oil-pipe being controlled by the cut-off valve 24. The nozzle 20 is constructed as shown in detail in Fig. 4 and comprises a T 25; the plug or reducer 26 in the outer end of the T; the elbow 27 in this reducer; the 75 air-pipe 21, connected to the central member of the T; the discharge-pipe 28, mounted in the T in alignment with the elbow 27; the rod 29, mounted in the elbow through the discharge-pipe; and the baffle-plate 30, mounted 80 upon the end of the rod 29 adjacent to the discharge end of the pipe 28.

The oil is forced through the pipe 22 by gravity, and a strong blast of air is forced through the pipe 21 by the fan or blower. The 85 volume of air being much larger than the volume of oil and having greater force will force the oil through the discharge-pipe 28 against the baffle-plate 30, and a mixture of oil and air will form a spray, discharging 90 through the inlet-flue 19 and into the ignition-chamber.

When it is desired to start the furnace, a quantity of waste may be placed in the ignition-chamber and ignited and the oil turned 95 on slowly, and as the waste and oil burns a red fire and black smoke will be produced, which will pass upwardly around the bridge-wall 12 and through the combustion-chamber, and as the blast coming through the pipe 14 100

mixes with this smoke and fire a blue flame will be established in the upper part of the combustion-chamber, and the heat from this flame will pass over the sand floor through 5 the heating-chamber. As soon as the ignition-chamber becomes well heated vaporizing is improved, more oil can be turned on, and a very hot fire will result sufficient to fill the upper part of the combustion-chamber and 10 the heating-chamber to the desired extent. When the furnace has been in operation a short time, the upper surface of the sand floor 7 will melt, and this melted silica forms a first-class flux to prevent sticking of the slag and 15 iron to the floor of the furnace and to clean the iron. If some of the silica passes off with the sand, the supply of sand may be replenished from time to time.

I desire to call especial attention to the fact 20 that the oil is vaporized and ignited in a chamber far removed from the heating-chamber, so that none of the liquid oil or the impurities of the oil will come in contact with the metal during the process of heating. It has been 25 found heretofore that a chemical action takes place where metal, either iron or steel, is heated by a smoky oil fire, but in a furnace in which the unconsumed vapor of the oil comes in contact with the metal, and that this chemical re- 30 action is injurious to the metal. In my furnace complete combustion takes place before the heating-chamber is reached, and nothing but the blue flame and the heat resulting therefrom will come in contact with the metal. I 35 wish to call attention also to the point at which the air-blast pipes 14 enter the furnace. This air-blast is directed through the upper part of the combustion-chamber onto the sand floor in such a way that it will hug the sand 40 floor, as required, to strike directly against any billets of metal resting upon the floor. This produces an entirely different result from what would be produced if the air-blast en-

tered the furnace in a different direction or at a different part of the masonry. For instance, 45 if the air-blast was directed through the flue 19 the intensest heat would be produced in the lower part of the combustion-chamber at a point directly opposite this flue, and a large part of the heat would be wasted by radiation 50 before reaching the heating-chamber. I have found from actual practice that the oil may be partially vaporized and partially burned, so as to produce a red fire and black smoke, 55 as in my ignition-chamber, and then the products of this imperfect combustion may be subjected to an air-blast producing a blue flame and perfect combustion and producing a great deal better result than where the air-blast is directed into the ignition-chamber in the first 60 instance.

I claim—

In an oil heating-furnace: the heating-chamber 5; the flue 8 leading from the heating-chamber; the bottom of the flue being lower 65 than the heating-chamber; a drain-pipe leading from the bottom of the flue; an overhanging bridge-wall 10 between the heating-chamber and the flue; the bridge-wall 12 at the opposite end of the heating-chamber from the 70 flue; the ignition-chamber 11 below the bridge-wall 12; the combustion-chamber 13 connecting the heating-chamber with the ignition-chamber; means of discharging oil and air into the ignition-chamber; and means of dis- 75 charging an air-blast into the heating-chamber directed toward the flue; substantially as specified.

In testimony whereof I have signed my name to this specification in presence of two sub- 80 scribing witnesses.

JAMES BEATTIE.
